HEINRICH EITEL, OF DUSSELDORF, GERMANY, ASSIGNOR TO FIRM "FENESTRA"
FABRIK FÜR EISENHOCHBAU G. M. B. H., OF DUSSELDORF-OBERCASSEL, GERMANY.

IRON WINDOW.

1,254,998.

Specification of Letters Patent.

Patented Jan. 29, 1918.

Application filed December 30, 1913. Serial No. 809,440.

To all whom it may concern:

Be it known that I, HEINRICH EITEL, a subject of the King of Prussia, residing at Dusseldorf, in the Kingdom of Prussia and 5 German Empire, have invented certain new and useful Improvements in and Relating to Iron Windows, of which the following is a specification.

10 My invention has for its object a window of fashioned iron which rests in a window frame composed of bars rabbeted stepwise, the space existing on both sides between the sash frame and the window frame being covered.

15 In my new window the sash frame is provided with rabbeted putty bars for the glass pane. These putty bars cover the putty completely so that the latter can not loosen and fall out. The sash frame may be 20 formed in such a manner that between it and the window frame a channel-like *e. g.* U-shaped cavity is provided for the reception and housing of fastening members, connecting angle pieces for the joints or anti-friction members, such as rollers or the like, 25 to insure the ready opening and closing of the window and prevent binding.

A window embodying my invention is 30 illustrated by way of example in the accompanying drawing, in which:

Figure 1 is a cross section,

Fig. 2 is a vertical section of the window in an iron frame subdivided by middle post and transom.

35 Fig. 3 is a vertical section of the window, the sash frame being formed with a channel-like cavity.

Fig. 4 is a vertical section of one part of the window, the fashioned iron for the sash 40 frame being provided with cover strips fixed thereon.

Fig. 5 is a partial horizontal section along line A—A in Fig. 4.

45 Figs. 6 and 7 illustrate a sash frame rail with rigid and detachable cover strip.

Figs. 8 and 9 show part of a cover strip and also a portion of a sash frame rail.

Figs. 10 and 11 illustrate two different constructional forms of the fashioned irons used for the formation of the window frame. 50

Fig. 12 is a perspective of the iron on which the putty rests.

The sash frame formed of the fashioned irons *a* is mounted in the fashioned irons *c* and *d* constituting the window frame and 55 being formed with a rabbet of stepped cross-section, as more particularly shown in Figs. 10 and 11. The fashioned irons *a* can be formed on their bearing faces, either solid (Figs. 1 and 2) or with a channel-like (*e. g.* 60 U-shaped) cavity *l* (Figs. 3 to 5). In the latter case the cavity *l* may serve for the reception and housing of locking or closing members or of antifriction devices such as rollers *m* or the like to facilitate the opening 65 and closing of the window. The sash is provided with a putty bar *b*, which may either be screwed, riveted or otherwise fixed to the fashioned iron *a* (Figs. 1 to 3), or may be made integral therewith (Figs. 4 and 5), 70 the said putty bar affording a means for covering and closing the joint between the outer fixed frame *c*, *d* and the movable sash *a*, thus serving as a packing medium. The vertical branch of the fashioned iron *a* 75 located opposite the putty bar *b* may, like this bar, be provided with an edge projecting toward the glass pane *g*, this projection covering the putty which rests in the cavity *x*, thereby preventing the putty from falling 80 out. Owing to the detachable fixing means of the putty bar *b*, the insertion or replacement of the window glass panes can readily be effected. When the sash frame iron *a* is formed as shown in Figs. 4 to 7, the amount 85 of putty placed around the glass pane can be limited by the insertion of separate strips *i* of wood, or metal. These strips are arranged as shown in the sash frame and are secured thereto by nails or screws. The 90 lower cross bar of each sash frame may be provided with a ledge *h* projecting outwardly and extending over the joint between the sash this ledge preventing rain or snow

from entering into the joint at the place where the sash frame and window frame meet.

In the construction shown in Figs. 3 to 5, the sash frame is formed with a channel *t* in which antifriction rollers *m* are mounted, whereby any binding between the sash frame and the window frame is avoided.

The combination of a metal sash, a rabbed putty bar detachably secured thereto,

the sash having inwardly projecting edges to securely hold the putty in place, and separate strips placed in the sash to reduce the amount of putty.

In testimony whereof I have affixed my 15 signature in presence of two witnesses.

HEINRICH EITEL.
